Farnum F. Dorsey

UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

SIGNAL HORN.

Application filed June 4, 1923. Serial No. 643,245.

To all whom it may concern:

Be it known that I, FARNUM F. DORSEY, a citizen of the United States, residing at Rochester, in the county of Monroe and State of New York, have invented certain new and useful Improvements in Signal Horns; and I do hereby declare the following to be a full, clear, and exact description of the invention, such as will enable others skilled in the art to which it appertains to make and use the same.

This invention relates to signal-horns of the type in which a diaphragm is vibrated by the action of a cam or a striker actuated by an electric motor.

In horns of the kind in question it is common to mount the cam, or its equivalent, on the end of the motor-shaft and to arrange the shaft in a position normal to the diaphragm. The degree of engagement between the cam and the cam-follower or wear-piece on the diaphragm may then be adjusted by longitudinal movement of the motor-shaft.

The principal object of the present invention is to improve the means for imparting longitudinal adjustment to the motor-shaft for the purpose aforesaid, and a subsidiary object is to provide, by the same construction, simple and effective means for fastening in place the cover or housing which encloses the electric motor. To these ends it is proposed to use this housing as a manually-operable means for effecting the adjustment in question, by so connecting it with one of the shaft-bearings that rotation of the housing about its axis causes longitudinal movement of said bearing and of the motor-shaft. By utilizing the connections, between the housing and the bearing, as the means for securing the housing in place, the subsidiary object aforesaid is accomplished.

Other objects and features of the invention will be set forth hereinafter, in connection with the description of the illustrated embodiment of the invention.

In the accompanying drawings Fig. 1 is a side-elevation of a signal-horn embodying the present invention, with parts shown in axial section, and Fig. 2 is a rear-elevation, with certain portions removed.

The invention is illustrated as embodied in a signal-horn having a diaphragm 4 to the middle of which a cam-follower 5 is

attached. The cam-follower cooperates with a toothed cam 6 fixed on the forward end of the shaft 7 of an electric motor. This shaft turns in bearings 8 and 9, and the bearing 8 is fixed in a sheet-metal member 10 constituting a part of the rigid frame of the horn and the motor. The motor has a rigid field-frame 11 which supports the bearing 9. The housing 12 which encloses the motor is in the form of a cylindrical cup drawn from sheet-metal.

The motor-shaft may be moved freely, in a longitudinal direction, through the bearing 8, and its position is determined by the bearing 9, which constitutes a thrust-bearing as well as a radial bearing. The bearing 9 is screw-threaded on the outside and supported in a threaded bushing 13 which is fixed in the middle of the field-frame 11. The bearing is counterbored to receive a screw 14, threaded into the end of the motor-shaft, and through this screw and a thrust-washer 26 the armature-shaft is longitudinally constrained by the bearing 9 while free to rotate therein.

Near its outer end the bearing 9 is provided with two longitudinal slots 15. The housing 12 is formed with a central depression 16 and with two integral tongues 17 which engage the slots 15. A coiled compression-spring 18, seated in the depression 16, is covered by a cap 19, which is fixed to the bearing 9 by a screw 20 threaded into the counterbore of the bearing. The screw 20 is preferably made hollow, as shown, to receive an oiler 21 of ordinary form, through which the bearing may be lubricated.

The housing is held in place at all times by the pressure of the spring 18, with its forward edge in firm engagement with a shoulder 22 on the member 10. The housing is free, however, except for friction, to rotate, so that it may be turned easily by hand. When so turned the movement is communicated to the bearing 9 by means of the tongues 17, so that the bearing is screwed forwardly or rearwardly in the bushing 13 according to the direction of rotation of the housing, and the horn is thus adjusted without removing the housing and without the use of tools of any kind.

The spring 18 yields to the longitudinal movement of the bearing 9, while maintaining a firm pressure against the hous-

ing. It has the further useful function of maintaining a constant rearward pressure against the bearing, thus taking up any lost motion in the direction of the thrust which occurs when the horn is in operation.

The friction between the housing and the frame-member 10 may be sufficient to retain the parts in adjusted position, but for further security a detent is used, in the form of a sheet-metal spring 23, which is centrally perforated to embrace the bearing 9. At its extremities the detent-spring has bosses 24 which cooperate with recesses 25 formed in the end of the housing. Rotation of the detent-spring is prevented by two lugs 27 punched and bent from the sheet-metal of the spring and engaging perforations in the field-frame 11.

The invention claimed is:

20 1. In a signal-horn, the combination, with a diaphragm, a frame to which the diaphragm is fixed a motor, mounted on said frame rotatable means, actuated by the motor, for vibrating the diaphragm, and a bearing, for said rotatable means, adjustable to control the operation thereof on the diaphragm, of a housing enclosing the motor and rotatably supported; and connections, between said housing and said bearing, through which rotation of the housing causes adjusting movement of the bearing.

35 2. In a signal-horn, the combination, with adjustable sound-producing devices and a motor for actuating said devices, of a housing enclosing said motor, the housing being rotatably supported and movable independently of the motor and being connected with the sound-producing devices so that rotation of the housing causes adjustment thereof.

40 3. In a signal-horn, the combination, with an electric motor having a stationary field-frame and a longitudinally-movable shaft, sound-producing devices actuated by said shaft and adjustable by longitudinal movement thereof, a thrust-bearing for controlling the longitudinal position of the shaft, said bearing being screw-threaded, and a stationary frame-member screw-threaded to

engage and support said bearing, of a housing enclosing the motor and said frame-member and rotatable coaxially with said bearing; said housing being connected with said bearing so as to impart rotation to the bearing and produce adjusting movement thereof through its screw-thread connection with said stationary frame-member.

4. A signal-horn, as defined in claim 3, further characterized by the fact that the connection between the housing and the thrust-bearing is such that the housing does not participate in the axial movement of the bearing.

5. In a signal-horn, the combination, with the parts recited in claim 3, of a spring connecting the housing and the thrust-bearing and pressing them constantly in opposite directions.

6. In a signal-horn, the combination, with the parts recited in claim 2, of frictional yielding means for retaining the housing normally against rotative movement.

7. A signal-horn, comprising the elements recited in claim 3, in which the connections between the housing and the thrust-bearing, 75 comprise a tongue-and-groove connection for imparting rotation from the housing to the bearing, and a spring tending to produce relative movement in the direction of the axis of the housing and the bearing.

8. In a signal-horn, the combination, with a diaphragm, a motor having a shaft and a frame, diaphragm-actuating means actuated by the shaft, and a thrust-bearing, for the end of the shaft remote from the diaphragm screw-threaded into the motor-frame and adjustable, by rotation, to adjust the position of the shaft and the operation of the diaphragm-actuating means, of a housing enclosing the motor and centrally perforated to receive said bearing, the housing and the bearing having connections for imparting rotation from the housing to the bearing without axial movement of the housing; and means engaging the housing adjacent 85 said bearing for retaining it against axial movement.

FARNUM F. DORSEY.
